Primary Examiner — Michelle E. Wilson*Assistant Examiner* — Charles Hwang(74) *Attorney, Agent, or Firm* — Birchwood IP(57) **CLAIM**

The ornamental design for a wireless charger as shown and described.

DESCRIPTION

FIG. 1 is a perspective view of a wireless charger showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the wireless charger in a second state;

FIG. 10 is an enlarged view of the wireless charger shown within the area designated as 10 in FIG. 2; and,

FIG. 11 is an enlarged view of the wireless charger shown within the area designated as 11 in FIG. 5.

The broken lines in the drawings are for the purpose of illustrating portions of the wireless charger that form no part of the claimed design. The dot-dashed broken line in FIGS. 10-11 show the boundary of the enlarged view and forms no part of the claimed design.
